Primary Examiner — Jennifer Rivard*(74) Attorney, Agent, or Firm* — Timothy Thut Tyson(57) CLAIM

The ornamental design for a hair volumizing accessory, as shown and described.

DESCRIPTION

FIG. 1 is a top, front, left side perspective view of a hair volumizing accessory showing my new design;

FIG. 2 is a bottom, rear, right side perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof; and,

FIG. 8 is a right side elevation view thereof.

The broken lines shown in the drawings illustrate hair clips and form no part of the claimed design.
